(57) **CLAIM**

The ornamental design for an illuminating device, as shown and described.

DESCRIPTION

FIG. 1 is a perspective view of the illuminating device;
FIG. 2 is a front view thereof;
FIG. 3 is a rear view thereof;
FIG. 4 is a top plan view thereof;
FIG. 5 is a bottom view thereof;
FIG. 6 is a left side view thereof; and,
FIG. 7 is a right side view thereof.
The broken line showing is for environmental purposes only
and forms no part of the claimed design.
